UNITED STATES PATENT OFFICE.

ROBERT MIEHLE, OF CHICAGO, ILLINOIS, ASSIGNOR OF ONE-HALF TO MIEHLE PRINTING PRESS & MANUFACTURING COMPANY, OF CHICAGO, ILLINOIS, A CORPORATION OF ILLINOIS.

CYLINDER-TRIPPING MECHANISM FOR PRINTING-PRESSES.

985,918.

Specification of Letters Patent.

Patented Mar. 7, 1911.

Application filed December 26, 1903, Serial No. 186,588. Renewed June 30, 1910. Serial No. 569,817.

To all whom it may concern:

Be it known that I, ROBERT MIEHLE, a citizen of the United States, residing at Chicago, in the county of Cook and State of Illinois, have invented certain new and useful Improvements in Cylinder-Tripping Mechanism for Printing-Presses, of which the following is a full, clear, and exact specification.

10 This invention relates to mechanism for tripping the cylinder of that form of cylinder printing presses in which the cylinder produces an impression every revolution. In my United States Patent No. 365,931, granted July 5, 1887, is shown a cylinder tripping mechanism for raising and lowering the cylinder at every alternate revolution, so that the type will not come into contact with the tympan or impression surface of the cylinder, this motion taking place as the normal and continual operation of the machine; but my present invention, which relates to that class of press where a portion of the impression cylinder is reduced 25 and the balance is used as the tympan or impression surface, has for its primary object to move the cylinder into and out of impression position at the will of the operator every revolution (instead of every other revolution) 30, as in my former patent,) so that during that portion of the revolution when the impression is ordinarily made, the impression cylinder will be removed from the type cylinder and during the balance of the revolution although the impression cylinder will occupy its closest or normal position to the type cylinder again, the impression surface or tympan thereof will be turned away from the type cylinder and hence the cylinders 35 will not touch at all during the time the impression cylinder is making this bodily up-and-down or to-and-fro motion.

With these ends in view my invention consists in certain features of novelty in the construction, combination and arrangement of parts by which the said objects, and certain other objects hereinafter appearing, are attained, all as fully described with reference to the accompanying drawings and 50 more particularly pointed out in the claims.

In the said drawings—Figure 1 is a side elevation of a printing press provided with my improved cylinder tripping mechanism. Fig. 1^a is a detail section taken lengthwise

of one of the toggles. Fig. 2 is a front elevation of the press, partly in section, and Fig. 3 is a detail plan section of the step.

1 is the type cylinder mounted in side frames 2 in operative relation to the usual or suitable inking rollers or apparatus 3, 60 and 4 is the impression cylinder having its journals mounted in suitable sliding boxes 5 held in inclined guides or ways 6, 7, formed in the side frames 2 in the usual or any suitable way. In the example shown 65 in the drawings these guide-ways are constituted by forming oblique rectangular slots, one in each of the frames 2, as clearly appears in Fig. 1, and into which slots the sliding boxes 5 are inserted from the 70 lower opened ends, which are afterward closed by pillow blocks 8. Journaled in these pillow blocks 8 and extending across the machine is a rocker-shaft 9, and to the ends of this rocker-shaft 9 are rigidly secured the lower links 10, 11, respectively, 75 of two toggle levers whose other or upper links 12, are pivotally connected to the lower sides of the boxes 5 and serve to support said boxes and the cylinder 4 in their upper 80 position with the impression on, and when in this position the toggle links are supported with their intermediate joint or pivot slightly beyond or below the center, by any suitable means, such as a stop 14 formed 85 on the lower one of the toggle links and arranged to rest against the lower guide-way 6 on which the box 5 slides, and thus maintain the cylinder 4 in its upper position.

To one end of the rocker shaft 9 at a point 90 preferably outside of the frame 2 is secured an arm or lever in the form of a yoke or fork, having two branches 15, 16, on the latter of which is mounted a stud in the form of an anti-friction roller 17, while in the upper branch 15 is formed a laterally elongated bearing or guide 18, and in this guide is situated a laterally movable stud 19 adapted to be pushed to and fro in its guide 18 by any suitable means, and rigidly secured 100 to the shaft or journal 20 of cylinder 4 is a cam having a major concentric periphery 21 and a minor concentric periphery 22, the major portion 21 being of such a radius that it will pass the stud 17 when the cylinder 4 105 is in its normal or upper position, as indicated in Fig. 1, without interfering with the position of the cylinder or oscillating or dis-

turbing the yoke arm 15, 16, and when in this normal position the yoke arm is supported by an adjusting screw 23 threaded in a suitable boss 24 on frame member 2, and 5 arranged to be impinged by the branch 16 of said yoke arm, so that the normal position of the roller 17 with relation to the cam can be gaged or adjusted to a nicety. The distance between the two studs 17, 19, is less 10 than twice the radius of the maximum portion 21 of the cam, so that when stud 19 is projected laterally into the line of movement of the cam's periphery and is engaged thereby by the yoke arm 15, 16, will be rocked or oscillated according to the formation of the 15 cam, the two concentric portions 21, 22, being connected together by rounding shoulders which are so formed that the cam will ease off on the stud 17 as fast as the stud 19 20 climbs on the cam, and consequently the rotation of the cam between the two studs and in engagement therewith will effect first an upward movement of the yoke arm 15, 16, which occurs when the major diameter 21 25 comes into engagement with the stud 19, and then a downward movement which occurs when the minor diameter or portion 22 of the cam comes under stud 19 and the major diameter 21 engages stud 17, serving to return the 30 yoke arm 15, 16 to its position against stop 23 in opposition to the weight of the cylinder 4. Hence it is seen that when the stud 19 is projected over the cam the rocker-shaft 9 will be oscillated and the cylinder 4 raised 35 and lowered once every revolution, it being lowered when the toggles break joint upwardly by the upward or outward motion of the yoke arm 15, 16, and raised when the toggles again straighten out into a straight 40 line, or slightly below a straight line, as indicated in Fig. 1, as a result of the major portion 21 of the cam depressing the stud 17. This rising and falling or to-and-fro movement of the impression cylinder 4 at 45 every revolution thereof will continue as long as the stud 19 is over the cam, but it will nevertheless be understood that no impression or printing will occur because when the impression cylinder is in its upper position, or closest position to the type cylinder 1, the tympan or impression part of the impression cylinder will be on the opposite side turned away from the type cylinder, and when this tympan or impression surface is 50 next the type cylinder the impression cylinder will occupy its outward position away from the type cylinder. The operation of the stud 19 for effecting this result may be placed under the control of the operator by 55 any suitable mechanism. As a desirable form of such is illustrated a bell-crank lever comprising two arms 25, 26, and an elongated rocker-shaft or journal 27, which is mounted in a suitable bearing 28 supported on a 60 bracket 29 fixed to or formed on the side of

yoke arm 15, 16. The upper end of arm 25 is broadened, as shown at 30, and engages in a notch 31 formed in the under side of stud 19 so that when the bell-crank 25, 26 is oscillated stud 19 will be pushed in and out. 70 Arm 26 is secured to the upper end of a connecting rod 32 whose lower end is pivoted to rocker arm 33 on a shaft 34 mounted in bearings 35 on the side frame 2. This shaft 34 is also provided with rocker arm 36 to 75 which is pivoted the lower end of a stem 37 having a shoulder 38 upon which rests a spring 39, and on this spring 39 is supported a step 40 whose shank 41 is hollow to receive the stem 37, so that the pressure upon 80 the step 40 can be communicated to the stud 19 through the described connections only through the intermediary of the spring 39, and consequently, should the step be depressed at the time when the lateral inward 85 movement of stud 19 would bring it against the side face of the cam, the spring 37 would yield to the pressure of the foot until the cam has rotated sufficiently to enable the stud 19 to shoot across it. When the step 40 is 90 relieved of the pressure of the foot the stud 19 and its operating connections just described are returned to their normal inactive position by a suitable spring 42 coiled on shaft 34 with one end secured thereto and 95 the other end secured to one of the bearings 35. Should it be desired, however, to maintain the stud 19 in engagement with the cam for any considerable length of time, as is often the case, the step 40 may be locked in 100 its depressed position in any suitable way, as, for example, by pushing it sidewise after it has been depressed. The step, it will be seen, is guided during its vertical movement by tongues or feathers 43 working in corresponding slots 44 in platform 45, which is also formed with a larger slot 46 in which the stem 41 of the step is situated so that if the step be depressed until the upper ends of its guide tongues 43 come below platform 110 45 the step may then be pushed laterally along slot 46 until guide tongues 43 engage under the platform at the sides of said slot 46, and thus prevent the step from rising until it is again returned laterally. It is 115 limited in its upward movement by a suitable stop 47 formed on shank 41 and arranged to strike the underside of the platform. It is of course understood that the pivot at the lower end of the stem 37 possesses sufficient lost motion to permit of this 120 oscillating movement of the step.

It will be seen that the invention provides a means under the control of the operator for moving the impression cylinder out of 125 impression position, that is to say away from the type cylinder, at every revolution, such means comprising primarily the stud 19, cam face 21, and connected or associated parts; and it also provides a means of mov- 130

ing the impression cylinder into impression position or toward the type cylinder at every revolution, which also comprises the cam face 21 and the stud 17, with connected or associated parts as before described in detail.

Having thus described my invention, what I claim as new therein and desire to secure by Letters Patent is:

- 10 1. In a cylinder tripping mechanism for printing presses, the combination with the bodily movable cylinder normally in impression position, of means beyond the control of the operator for moving the cylinder into impression position at each revolution thereof, and means under the control of the operator for moving the cylinder out of impression position at each revolution thereof.
- 15 2. In a cylinder tripping mechanism for printing presses, the combination with the bodily movable cylinder normally in impression position and means beyond the control of the operator for moving the cylinder into impression position at each revolution thereof, of a cam revolving in unison with the cylinder, and means operatively related to said cam and upon which the cam acts for throwing the cylinder into "off impression" position, said means being movable into and out of engagement with the cam at the will of the operator.
- 20 3. In a cylinder tripping mechanism for printing presses, the combination with the bodily movable cylinder normally in impression position, and means beyond the control of the operator for moving the cylinder into impression position at each revolution thereof, of a cam revolving in unison with the cylinder, and means operatively related to said cam and upon which the cam acts for throwing the cylinder into "off impression" position, said means being movable into and out of engagement with the cam at the will of the operator.
- 25 4. In a cylinder tripping mechanism for printing presses, the combination with the bodily movable cylinder normally in impression position, of a cam revolving in unison with the cylinder, means operatively related to said cam and upon which the cam acts for throwing the cylinder into "off impression" position, and means comprising an elastic connection for moving said second means into engagement with the cam at the will of the operator.
- 30 5. In a cylinder tripping mechanism for printing presses, the combination with the bodily movable cylinder normally in impression position, of a cam revolving in unison with the cylinder, means operatively related to said cam and upon which the cam acts for throwing the cylinder into "off impression" position, means for moving said means into and out of engagement with said cam at the will of the operator, and means for locking said first means in engagement with the cam at the will of the operator.
- 35 6. In a cylinder tripping mechanism for printing presses, the combination with the bodily movable cylinder normally in impression position, of a cam revolving in unison with the cylinder, means operatively related to said cam and upon which the cam acts for throwing the cylinder into "off impression" position, and means for moving said second means into engagement with the cam at the will of the operator.
- 40 7. In a cylinder tripping mechanism for printing presses, the combination with the bodily movable cylinder, of a toggle lever for moving said cylinder bodily, having one link connected therewith, a cam secured directly to the cylinder and revolving therewith, an arm connected with the other link of said toggle, a fixed stud on said arm engageable by the cam but out of the influence of the cam when the cylinder is in impression position, a second stud carried by said arm and movable laterally across the periphery of the cam and adapted to be engaged thereby for rocking the arm and throwing the cylinder out of impression, and means for shifting said second stud at will.
- 45 8. In a cylinder tripping mechanism for printing presses, the combination with the bodily movable cylinder, of a rocker-shaft, two toggle levers rigidly secured to the ends of said shaft respectively, and pivotally connected with the ends of the cylinder, a cam revolving with the cylinder, a yoke arm secured to said rocker shaft, a stud carried by said arm and adapted to be engaged by said cam, a second stud movable laterally in the arm across the periphery of the cam and adapted to be engaged by the cam for rocking the arm and moving the cylinder through the intermediary of said toggles, and means for shifting said second stud at will.
- 50 9. In a cylinder tripping mechanism for printing presses, the combination with the bodily movable cylinder, of a cam revolving with the cylinder, a pivoted arm operatively connected with the cylinder for moving the same bodily, a stud carried by said arm and engageable by said cam, a shifting stud carried by the arm and movable across the plane of movement of the cam and adapted to be engaged thereby, a bell-crank journaled on said arm and operatively connected with said shifting stud, and a step operatively connected with said bell crank.
- 55 10. In a cylinder tripping mechanism for printing presses, the combination with the bodily movable cylinder normally in impression position, and means beyond the control of the operator for moving the cylinder into impression position at each revolution thereof, of means operating with the cylinder

der to throw the cylinder out of impression at each revolution of the cylinder, and means under the control of the operator for controlling said second means.

6. In a cylinder tripping mechanism for printing presses, the combination with the bodily movable cylinder, of a toggle lever for moving said cylinder bodily, having one of its links connected therewith, a cam revolving with the cylinder, an arm connected with the other link of said toggle, a stud on said arm engageable by said cam but out of the influence of the cam when the cylinder is in impression position, a second stud on said arm movable into engagement with the cam for rocking the arm and throwing the cylinder out of impression, and means for controlling said second stud at will.

7. In a cylinder tripping mechanism for printing presses, the combination with the bodily movable cylinder, of a toggle lever for moving said cylinder bodily, having one link connected therewith, a cam secured directly to the cylinder and revolving therewith, an arm connected with the other link of said toggle, a fixed stud on said arm engageable by the cam but out of the influence of the cam when the cylinder is in impression position, a second stud carried by said arm and movable laterally across the periphery of the cam and adapted to be engaged thereby for rocking the arm and throwing the cylinder out of impression, and means for shifting said second stud at will.

8. In a cylinder tripping mechanism for printing presses, the combination with the bodily movable cylinder, of a rocker-shaft, two toggle levers rigidly secured to the ends of said shaft respectively, and pivotally connected with the ends of the cylinder, a cam revolving with the cylinder, a yoke arm secured to said rocker shaft, a stud carried by said arm and adapted to be engaged by said cam, a second stud movable laterally in the arm across the periphery of the cam and adapted to be engaged by the cam for rocking the arm and moving the cylinder through the intermediary of said toggles, and means for shifting said second stud at will.

9. In a cylinder tripping mechanism for printing presses, the combination with the bodily movable cylinder, of a cam revolving with the cylinder, a pivoted arm operatively connected with the cylinder for moving the same bodily, a stud carried by said arm and engageable by said cam, a shifting stud carried by the arm and movable across the plane of movement of the cam and adapted to be engaged thereby, a bell-crank journaled on said arm and operatively connected with said shifting stud, and a step operatively connected with said bell crank.

10. In a cylinder tripping mechanism for printing presses, the combination with the

- bodily movable cylinder, of a cam fixed thereto, a rocker shaft operatively connected with the cylinder for moving it bodily, an oscillatory arm secured to said shaft and means carried by said arm for engaging the cam and causing the arm's oscillation, the last said means and said cam being disengageable and one being movable into and out of the path of action of the other.
- 10 11. In a cylinder tripping mechanism for printing presses, the combination with the bodily movable cylinder, of a means for tripping the same and moving it out of printing position, of positive automatic operating means for moving the cylinder into impression or printing position during
- 15

every revolution after the cylinder has been moved out of impression position by said tripping means.

12. In a cylinder tripping mechanism for printing presses, the combination with the bodily movable cylinder, of means beyond the control of the operator for moving the cylinder into impression position at every revolution thereof, and means for moving the cylinder out of impression position at each revolution thereof. 20 25

ROBERT MIEHLE.
